GARMENT HANGER SUPPORT

Selma L. Cohen and Felix A. Orlewitz,
New York, N. Y.

Application September 5, 1952, Serial No. 308,118

3 Claims. (Cl. 211—100)

1

This invention relates to improvements in collapsible supports for garment hangers.

A primary object of the invention is the provision of a collapsible support which may be conveniently mounted on the inner side of the door of a closet or other compartment and which is designed and constructed in such a manner as to assure maximum utilization of a limited amount of storage space.

Another object of the invention is the provision of a device of the character indicated wherein the garment supporting element is pivotally attached to a base supporting element and may be swung to an inclined operative position or alternatively may be collapsed to a compact condition substantially parallel to the base element, thereby occupying a minimum of space.

A further object of the invention is the provision of a device of the character indicated having a novel and durable arrangement for limiting the movement of the garment supporting element between its inclined operative position and its retracted or collapsed position.

An additional object of the invention is the provision of a device of the character described having a simple and positive latching means arranged to substantially automatically lock the garment supporting element in vertical retracted position by the action of gravity and which need only be raised slightly to allow the garment supporting element to be swung to operative position.

Another object of the invention is the provision of a device of the character described which is lightweight and durable and which may be fabricated simply, rapidly and inexpensively.

The foregoing objects as well as additional objects and advantages of the invention will be readily apparent in the course of the following detailed description taken in connection with the accompanying drawing which illustrates a preferred embodiment of the invention, and wherein:

Fig. 1 is a perspective view of the collapsible support with the garment supporting element shown in open or inclined operative position;

Fig. 2 is a front elevational view of the device in collapsed condition;

Fig. 3 is a side view of the device in open operative condition together with an enlarged detail view of the manner of connecting the tie or strap member to the garment supporting element;

Fig. 3a is a showing on an enlarged scale of the portion of the structure of Fig. 3 the arm 16 with its pivotal connection to member 12.

Fig. 4 is an enlarged detailed perspective view of the lower portion of the device;

Fig. 5 is an enlarged detail view of the upper portion of the device and illustrates the interrelationship of the base supporting element, the garment supporting element and the latching member; and

Fig. 6 is a sectional view similar to Fig. 5 but

2

illustrating the operation of the latching member.

Referring now to the drawing in greater detail, the collapsible support includes the base member or mounting element 10 which is preferably flat and elongated and which may be formed, if desired, from synthetic plastic material or the like, as may the other component elements of the device. Adjacent its upper and lower ends respectively, and intermediate thereof, base member 10 is provided with the mounting apertures 11 for the reception of screws or other fastening elements so that the base member may be readily secured in substantially vertical position to the wall or the inside of the door of a closet or other storage compartment.

Adjacent the lower end of base member 10, an elongated bar or garment supporting member 12 is swingably mounted as by means of the hinge or pivotal connection 13. In order to prevent torsional distortion of the supporting member 12 under load, base member 10 is provided adjacent its lower end with a pair of preferably integral guiding members or tongues 14 which extend within a pair of slots 15 formed in supporting member 12, as best shown in Fig. 4. It will also be noted that supporting member 12 is preferably channel-shaped for maximum strength and that the side flanges 12a thereof fit over the sides of base member 10 in the collapsed condition of the device, as shown in Fig. 5.

An important feature of the invention resides in the manner of interconnecting supporting member 12 with base member 10 so as to provide for the swingable extension of said supporting member in its operative inclined position of Fig. 3 and, alternatively, to provide for its retraction into substantially vertical inoperative position (Figs. 2 and 5). For this purpose a slidably, rigid tie member or arm 16 is hingedly connected at its outer end as at 17 to supporting member 12. As best seen in the enlarged detail view as shown in Fig. 3a of the pivotal connection of arm 16 to member 12 of Fig. 3, hinge connection 17 preferably comprises the hinge bracket 18 which may be secured to supporting member 12 in any suitable manner, as for example, screw 19 or a rivet. Since supporting member 12 may be formed of synthetic plastic material, hinge bracket 18 may be secured thereto by heat sealing means such as a plastic rivet in lieu of screw 19.

The front face of base member 10 is provided with a rectangular recess 20 for the reception of slidably arm 16 in the collapsed condition of the device. In the lower portion of recess 20, base member 10 is formed with a slot 21 for slidable reception of the lower end of tie member 16. For this purpose tie member 16 is formed adjacent its lower end with a pair of inwardly extending slots 22 (see Fig. 4) and a terminal locking protuberance or enlargement 23. It will of course be understood that the rear surface of base member 10 will also be recessed, as at 34 (Fig. 4), in the area of slot 21 in order to provide for sliding

clearance of the terminal enlargement 23 of tie member 16 when the device is mounted on a supporting surface.

By reason of the described arrangement it will be seen that slot 21 serves together with slidable tie member 16 to limit the outward swingable extension of supporting member 12 to the position illustrated in Fig. 3, the angle of inclination of said supporting member with respect to base member 10 depending upon the height of the slot 21.

In order to provide for releasably retaining supporting member 10 in collapsed vertical position, a slidable latching member 24 is provided at the upper end of base member 10. Accordingly, base member 10 is provided at its upper end with an inwardly extending recess 25 (see Figs. 5 and 6) and the latching member 24 is formed adjacent its rear lower edge with a pair of inwardly extending lateral lugs 26 which are slidably received within recess 25 for slidable inter-engagement between said latching member and base member 10. The extreme upper end of supporting member 12 defines a projecting tongue 27 beveled as at 28 (see Fig. 6) which will be retained by the lower end of front wall 24a of latching member 24 in the collapsed condition of the device. In order to release supporting member 12, it is only necessary to lift slidable latching member 24 sufficiently to clear the projecting tongue 27 of supporting member 12, whereupon said supporting member may be readily swung or lowered to its operative inclined position illustrated in Fig. 3.

As illustrated in the drawings, supporting member 12 is provided on its front surface with a plurality of studs or protuberances 29 each of which defines a notch 30 for the reception of the hook portion of a garment hanger or the like. By reason of the novel construction and arrangement of the present invention the device may be employed for supporting an unusually large number of garments within a relatively restricted space or enclosure. The swingable connection between supporting member 12 and base member 10 together with the limiting movement imposed upon said supporting member by the slidable tie member 16 and the presence of the latching member 24 combine to allow the device to be readily collapsed into relative compacted condition, thereby greatly conserving valuable space, and alternatively the arrangement described allows swingable extension of the garment supporting member 12 to open operative position for easy hanging or removal of garments therefrom.

Since certain modifications may be made in the device of the present invention without departing from the scope thereof, it is intended that all matter contained in the foregoing specification and shown in the accompanying drawing be interpreted merely as illustrative and not in a limiting sense; and, accordingly, that the appended claims are to be construed as defining the invention within the full spirit and scope thereof.

What is claimed is:

1. A collapsible device for supporting garments and the like comprising a base member adapted to be mounted in substantially vertical position on a supporting surface, a garment supporting member swingably attached to said base member adjacent the lower end thereof, a tie member interconnecting said base member and said supporting member, said tie member being dimensioned to retain said supporting member in op-

erative inclined limiting position with respect to said base member at a predetermined angle of inclination, said base member being formed with a pair of integral guiding tongues adjacent the lower end thereof, said supporting member being formed with a pair of complementary slots for the reception of said guiding tongues in order to prevent torsional distortion of said supporting member under load, and latching means carried by said base member for releasably retaining said supporting member in substantially vertical collapsed condition.

2. A collapsible device for supporting garments and the like comprising a base member adapted to be mounted in substantially vertical position on a supporting surface, a garment supporting member swingably attached to said base member adjacent the lower end thereof, a tie member pivotally connected at its lower end to said base member to define an operative inclined limiting position for said supporting member and slidably connected at its lower end to said base member to define an operative inclined limiting position for said supporting member at a predetermined angle of inclination with respect to said base member, said base member being formed with a pair of integral guiding tongues adjacent the lower end thereof, said supporting member being formed with a pair of complementary slots for the reception of said guiding tongues in order to prevent torsional distortion of said supporting member under load, and latching means carried by said base member for releasably retaining said supporting member in substantially vertical collapsed condition.

3. A collapsible device for supporting garments and the like comprising a base member adapted to be mounted in substantially vertical position on a supporting surface, a garment supporting member swingably attached to said base member adjacent the lower end thereof, a tie member pivotally connected at its upper end to said supporting member, said base member having in the lower portion thereof a longitudinal slot for slidable engagement of the lower end of said tie member, said slot being dimensioned to define an operative inclined limiting position for said supporting member at a predetermined angle of inclination with respect to said base member, said base member being formed with a pair of integral guiding tongues adjacent the lower end thereof, said supporting member being formed with a pair of complementary slots for the reception of said guiding tongues in order to prevent torsional distortion of said supporting member under load, and latching means carried by said base member for releasably retaining said supporting member in substantially vertical collapsed condition.
